COMBINED BRIDGE AND TREMOLO UNIT FOR A STRINGED MUSICAL INSTRUMENT

James Ormston Burns, Buckhurst Hill, Essex, England,
assignor to Ormston Burns Limited, London, England,
a British company

Filed Dec. 12, 1962, Ser. No. 72,822

Claims priority, application Great Britain July 28, 1962

Term of patent 14 years

(Cl. D56—1)

FIG. 1.

FIG. 2.

FIG. 3.

FIG. 1 is a front perspective view of a combined bridge and tremolo unit for a stringed musical instrument embodying my new design;

FIG. 2 is a rear perspective view, and
FIG. 3 is an underneath plan view.

I claim:

The ornamental design for a combined bridge and tremolo unit for a stringed musical instrument, substantially as shown.
